CLAIM

The ornamental design for a packaging box, as shown and described.

DESCRIPTION

FIG. 1 is a perspective view of the packaging box.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines showing portions of a packaging box depicts only environment and forms no part of the claim. The dot-dash broken lines in the drawings represent an unclaimed boundary line and form no part of the claimed design.
